CLAIM

The ornamental design for a music notation whiteboard, as shown and described.

DESCRIPTION

FIG. 1 is a perspective view of a music notation whiteboard, showing my new design;

FIG. 2 is a front view thereof;

FIG. 3 is a back view thereof;

FIG. 4 is a left side view thereof; the right side view being identical to the left view; and,

FIG. 5 is a top view thereof; the bottom view being identical to the top view.
